UNITED STATES PATENT OFFICE

168,395

TOILET COMB

Eric Leopold Hugo Cosby, London, England

Application July 10, 1952, Serial No. 20,554
In Great Britain February 19, 1952

Term of patent 14 years

(CL. D86—8)

To all whom it may concern:

Be it known that I, Eric Leopold Hugo Cosby, a subject of the King of Great Britain, residing at London, England, have invented a new, original, and ornamental Design for a Toilet Comb, of which the following is a specification, reference being had to the accompanying drawings, forming a part thereof.

I claim:

The ornamental design for a toilet comb, as shown.

ERIC LEOPOLD HUGO COSBY.
